Specification of Letters Patent. Patented Sept. 22, 1914.

Application filed June 17, 1908. Serial No. 438,890.

To all whom it may concern:

Be it known that we, ALBERT E. MCGILL and FRANK J. BEIER, citizens of the United States, and residing, respectively, at Chicago, Cook county, Illinois, and Elkhart, Elkhart county, Indiana, have invented certain new and useful Improvements in Folding Go-Carts, of which the following is a specification.

- 10 This invention relates to improvements in folding go-carts and the primary object of the same is to provide an improved device of this character which may be readily and compactly collapsed for storing or shipping purposes.
- 15 A further object is to provide an improved device of this character including laterally foldable sides and improved means for securing the sides in position for use.

A further object is to provide an improved 20 yielding support for the seat.

A further object is to provide an improved adjustable and foldable foot rest, and improved means for holding the parts of the foot rest in position for use.

- 25 A further object is to provide an improved cart of this character including wheel supports, foldable with respect to the supporting frame and balls for holding the wheel supports in position for use, and improved means for locking the bails against 30 displacement.

A further object is to provide an improved adjustable back and improved means for locking the back in position for use, and 35 also improved means for releasing the back to permit the latter to be folded with respect to the supporting frame.

A further object is to provide an improved 40 device of this character which will be simple and durable in construction and effective and efficient in operation.

To the attainment of these ends and the accomplishment of other new and useful objects, as will appear, the invention consists 45 in the features of novelty in the construction, combination and arrangement of the several parts hereinafter more fully described and claimed and shown in the accompanying drawings illustrating an embodiment of the invention and in which—

Figure 1 is a side elevation of an improved device of this character constructed in accordance with the principles of this invention. Fig. 2 is a longitudinal sectional

view of Fig. 1. Fig. 3 is a top plan view. 55 Fig. 4 is a detail sectional view on line 4—4 of Fig. 1. Fig. 5 is a detail sectional view on line 5—5 of Fig. 1. Fig. 6 is a side elevation, showing the cart partially collapsed or folded. Fig. 7 is an enlarged detail view, partly in section, showing one of the yielding supports for the seat. Fig. 8 is a detail sectional view on line 8—8 of Fig. 7 showing the locking bail for supporting the seat back. Fig. 9 is a detail plan 65 view partly in section, showing the locking means for retaining the locking bail of the wheel supports in position. Fig. 10 is an enlarged detail top plan view showing the manner of connecting the handle and the 70 catch for locking the handle in a position for use, to the frame. Fig. 11 is an enlarged detail sectional view on line 11—11 of Fig. 2. Fig. 12 is a detail perspective view of a portion of the strut for the front part 75 of the supporting frame and the foot rest, showing the manner of locking the foot rest in position for use. Fig. 13 is a detail perspective view showing the manner of securing a portion of one of the supporting 80 springs to the main frame. Fig. 14 is an enlarged detail perspective view of a portion of the foot rest.

Referring more particularly to the drawings and in the present exemplification of 85 the invention, the main supporting frame preferably comprises spaced side bars 20, the forward extremities of which may be connected by means of a cross bar or member 21 which is preferably located a short 90 distance from the front extremities of the side bars and a substantially U-shaped bar or member 22 is located between the side bar 20 with the extremities thereof secured to the extremities of the side bars, as shown 95 more clearly in Fig. 3. The body portion of this member preferably curves away from the extremities of the side bars 20 so as to engage the cross bar 21 between the side bars 20, as shown more clearly in Fig. 12 100 of the drawings, and these bars or members 21, 22, are secured together in any desired or suitable manner, preferably by means of fastening bolts or members 23 in the form of rivets. These members 21, 22, are preferably constructed of thin strips of material, such as metal or the like, and are arranged on edge so that the contacting portions will 105

form a catch engaging portion 24 intermediate the side bars 20.

A handle having side members 25 is pivotally connected to the other extremities of the side bars 20 preferably by means of a connecting bar or rod 26 which extends across the space between the side bars and this connecting rod also serves as a means for connecting the rear extremities of the side bars.

10. Wheel supports 27 are rotatably supported by the side bars, whereby the wheels 28, which are mounted in the supports 27, may be folded with respect to the running gear frame and these supports may be held 15 against longitudinal displacement with respect to the frame by means of clips 29, shown more clearly in Figs. 1 and 3. The supports on each side of the frame may be connected by means of a connecting bar or member 30 for simultaneous adjustment with respect to the supporting frame and the extremities of these connecting bars or members 30 may be deflected as at 31, shown more clearly in Fig. 9 of the drawings, and secured to one face adjacent the deflected portions are clips 32 which extend toward the free ends of the members 30.

Pivotal supported by the side bars 20 are bails 33 which depend below the side bars and are connected by a cross bar 34 to resist the lateral strain of the wheel supports 27 when the latter are locked in position for use. If desired, suitable braces 35 may be provided for the bails. One of these bails is located at the front and rear of the supporting frame and the members 33 thereof are adapted to enter the space between the extremities 31 and the clips 32 on the members 30 to lock the wheel supports in position. A suitable catch or latch 36 may be pivotally connected as at 37 (shown more clearly in Figs. 6 and 9) to the extremities of the members 30 and, is adapted to assume a position behind the bails 33 when the latter are in position to lock the wheel supports 27, to prevent the bails from becoming accidentally detached. When it is desired to release the bails the latches or catches 36 must be first moved out of position to permit the adjustment of the bails. Supported by the frame work thus formed are elastic members 38, such as springs or the like, one of which is arranged adjacent each of the side bars 20 and to extend longitudinally of the supporting frame. These springs may be secured to the frame in any desired or suitable manner, preferably by means of clips 39 through which the body portion of the springs pass and these clips 55 may be secured to any fixed portion of the supporting frame, preferably the bar or member 21. One end of each of the springs 38 is preferably secured to the cross bar or rod 26 by means of the extremities thereof 60 passing around the cross bar, as shown more

clearly in Fig. 3. The body portion of these springs between the cross bar 26 and the clips 39 is substantially parallel with the side bars 20 and the portion of the springs beyond the clips 39 are bent back 70 upon the body portion of the spring so as to extend over the clips and toward the rear of the supporting frame to form extremities 40 which are substantially parallel with and spaced above the body portion of 75 the springs.

A seat 41 rests upon and is secured to the extremities 40 of the springs and is yieldingly supported thereby. The rear of the seat preferably extends beyond the extremity 40 of the springs and secured to the seat beyond these extremities and projecting a short distance beyond the rear edge of the seat is a member 42 (shown more clearly in Figs. 2 and 8 of the drawings) and if desired, a suitable reinforcing member 43 in the form of an angle iron may be secured to the seat below the member 42 and this member, beyond the seat, is provided with an upright portion 44 which preferably extends a short distance above the seat, and pivotally supported between these upright portions 44 is a back 45 for the seat, which latter is adapted to fold inwardly upon the seat. Each of the members 42 is provided 95 with a lip or upwardly projecting portion 46 beyond the upright portion 44 and pivotally supported by the back 45 is a bail 47, which depends below the seat, and the side members 48 of the bail are each provided with a plurality of rack teeth 49 adapted to coöperate with the upwardly projecting lip 46 on the member 42 for locking the back 45 at any desired angle with respect to the bottom 41 of the seat. 100

If desired, additional cushioning means 50, such as upright coil springs, may be provided adjacent the rear edge of the seat to coöperate with the springs or elastic supports 38. These upright springs 50 are 110 preferably supported by the springs 38 and are preferably coiled around an upright support 51, one extremity of the springs extending within a housing 52 which is supported by the spring 38 and the other extremity of these springs engaging a suitable portion 53 fixed with relation to the bottom 41 of the seat and this portion 53 preferably has a sliding connection with the uprights 51. With this improved construction it will be apparent that the seat 41 is not only yieldingly supported with relation to the running gear frame but the extremity 40 of the springs 38 will be relieved by means of the additional springs or elastic members 50. 120

The back 45 may be adjusted with respect to the seat 41 from the position shown in Figs. 1, 2 and 8 of the drawings, by raising the back 45 about its point of pivotal sup- 130

port, which movement will cause the rack teeth 49 to ride over the upwardly projecting portion 46 of the member 44, and a suitable elastic member 54, such as a coil spring 5 or the like, may be provided for holding the rack teeth 49 in engagement with the upright portion 46. Any number of these springs 54 may be provided and one extremity thereof may be secured to the bail 10 47 and the other extremity to the lower face of the seat, as shown more clearly in Figs. 1 and 2 of the drawings.

Any suitable means may be provided for detaching the bail 47 from the lip or projection 46 to permit the back to be lowered. A suitable and efficient means for accomplishing this purpose comprises a handle 55 which may be slidably mounted upon the rear face of the back 45, and a suitable flexible connection 56 may be provided between the extremity of the handle 55 and the bail 47, whereby the latter may be adjusted at the will of the operator.

Suitable supports 57 may be secured to the seat 41 in any desired or suitable manner, preferably by means of angle pieces 58, shown more clearly in Figs. 2 and 7 and these supports extend longitudinally with respect to and preferably beyond the ends of the seat and serve as means for supporting the sides 59 of the seat, which sides are preferably in the form of panels. These sides may be pivotally connected with the supports 57 so as to fold laterally in any desired or suitable manner, preferably by means of hinges 60, so that the sides may be folded inwardly and superposed upon the seat 41. The side panels 59 are of a length to project for some distance beyond the back 40 45 of the seat when the latter is in an upright position to prevent the child or occupant from extending his arms through the space formed between the back and the side and thereby avoid the danger of the child 45 becoming injured.

Secured to the inner face of the sides 59 and adjacent the forward and rear edge thereof are clips 61, 62, (shown more clearly in Figs. 2 and 11 of the drawings) which are preferably spaced from each other. Pivotally supported by the forward edge of the seat is a bail 63, the side arms 64 of which are adapted to engage the inner face of the respective side 59 and to engage the clips 61 to lock the bail against displacement and for holding the sides 59 in an upright position. A similar bail 65 is pivotally supported adjacent the rear of the sides 59 and the side arms 66 thereof are adapted to rest against the inner faces of the sides to engage the clips 62 and coöperate with the front arms 64 for holding the sides in position. A portion 67 of each of the arms of the respective bails may be offset, as shown, to form a handle by means of which the bails

may be readily detached from the respective clips and moved about their points of pivotal support into the positions shown in Fig. 6 of the drawings to permit the sides 59 to be folded inwardly upon the bottom 70 41 of the seat.

A foot rest 68 is pivotally supported adjacent the forward edge of the seat 41 and depends below the seat as shown. This foot rest is of a box-shaped formation, comprising a bottom and spaced sides 69. The sides 69 are preferably sectional, the outer sections 70 being pivotally connected to the inner sections 69 so as to fold inwardly by means of suitable pivots, such as hinges 71 80

or the like, and the bottom 68 is provided with a section 72 which is pivotally connected to the outer edge thereof in any desired or suitable manner, preferably by means of a bar or rod 73 passing through 85 cooperating clips 74 which are respectively

cooperating clips 74 which are respectively secured to the sections of the bottom. Suitable reinforcing members 75 may be provided on the edges of the section 72 and clips or latches 76 may be provided which are pivotally supported by the sections 70

and adapted to overlap the reinforcing members 75 for holding the outer sections 70 and 72 in position for use. When it is desired to collapse or fold the foot rest, the 95 clips 76 may be moved about their points of pivotal support to disengage the outer sections 70 and 72.

pivotal support to disengage the sections 72 and then the sections 70 may be first folded inwardly, as shown more clearly in Fig. 6, after which the sections 72 may be 100 folded upon the inwardly folded sections 70. Any suitable means may be provided

105
means may be provided for moving the foot rest about its point of pivotal support for raising or lowering the rest to permit the occupant to assume an upright or a reclining position. A suitable and efficient means for accomplishing this

purpose will now be described. Pivotally connected by one extremity, as at 77, to a support 78 which is secured to the rear face 110 of the bottom of the foot rest 68, is a rack or toothed catch 79, the teeth 80 of which are arranged on the lower face thereof and

arranged on the lower face thereof and this catch is adapted to extend across and rest upon a catch engaging portion of the front strut 21, 22, of the running gear frame, so that the catch engaging portion 24 thereof will enter the space between two

adjacent teeth 80. This catch may be of any desired length according to the height 120 to which it is desired to elevate the foot rest, and a suitable guard or bail 81 may be provided, which extends below the catch engaging portion 24 with its extremities se-

gaging portion 21 with its extremities secured to the catch on each side thereof. 125 Any suitable means may be provided for moving the catch about its point of pivotal support into or out of engagement with the catch engaging portion 24. A suitable and efficient means for accomplishing this pur- 130

pose comprises a cranked shaft 82, one arm 83 of which is loosely connected to the catch beyond its pivot and another arm 84 may extend beyond one side of the foot rest to form a handle, by means of which shaft 82 may be rotated in its bearings 85. Any suitable means may be provided for locking the handle 25 in position for use and a suitable and efficient means for accomplishing this purpose will now be described.

Loosely surrounding each of the side bars 20 of the main supporting frame is a sleeve or collar 86, provided with upwardly projecting ears 87, which extend above the side bars. These ears are preferably provided with registering apertures 88 and extending through the registering apertures of both of these sleeves or collars is the body portion 89 of a bail, the side arms 90 of which are located beyond the sleeves or collars and the extremities thereof are pivotally connected as at 91 to the members 25 of the handle. The body portion 89 of the bail is preferably located in close proximity to the upper edges of the side bars 20 of the supporting frame and the springs 38 project over and rest upon the body portion of the bail, as shown more clearly in Fig. 2 of the drawings, whereby friction will be created upon the bail to retard the movement of the sleeves or collars 86 when the handle is adjusted.

Suitable catches 92 are pivotally supported by one extremity, preferably by means of the cross bar or rod 26. One of these catches is located adjacent each of the side bars 20 and preferably above the bars and each catch is provided with a notch 93 adjacent the end thereof and an inclined or beveled extremity 94, so that when the sleeves or collars 86 are moved to the rear, the portion of the bail 89 between the upwardly projecting ears 87 of the respective collars or sleeves will engage the inclined or beveled portion 94 of the catches and move the latter about their points of pivotal support against the tension of their retaining springs 95 to permit the notches 93 to engage over the bail between the ears 87. These catches 92 may be connected by means of a connecting bar or rod 96 which extends across the supporting frame and a treadle 97 may be provided for disengaging the catches from the bail to release the handle to permit the latter to be folded.

If desired, the bails 33 may be provided with suitable notches 98 for receiving the extremities of the latches or catches 36.

With this improved construction it will be apparent that when the parts are in position for use, they will be firmly secured, yet at the same time the cart may be readily collapsed into a compact space for storage or shipment purposes. It will also be apparent that the seat will be yieldingly sup-

ported with respect to the running gear frame by means of the springs which extend longitudinally of the frame, whereby greater resiliency will be imparted thereto and at the same time the springs will be firmly held and braced by means of the clips 39. Furthermore, it will also be apparent that the shape of the front strut will permit the foot rest to be lowered to a position that a portion thereof will extend between the side bars of the supporting frame, thereby obviating the necessity of extending the seat 41 to the extreme end of the side bars.

In order that the invention might be understood, the details of the foregoing embodiment have been thus specifically described but

What we claim as new is—

1. A vehicle including in combination a supporting frame, a seat yieldingly supported thereby, laterally foldable sides supported by the seat, means for locking the sides in position for use including catches on the sides and a bail for engaging the catches, an adjustable back for the seat, a foldable foot rest, and means for varying the position of the rest with respect to the seat.

2. A vehicle including a supporting frame, a seat supported thereby, sides for the seat adapted to be folded inwardly upon the seat, means for holding the sides in position for use including catches on the sides and a bail for engaging the catches, a back for the seat also adapted to fold inwardly upon the seat, a foldable foot rest pivotally supported with respect to the seat, and means for adjusting the rest about its pivot for varying the position thereof with respect to the seat.

3. A vehicle including in combination a supporting frame, a seat supported thereby, laterally foldable sides for the seat, means for locking the sides in position for use including catches on the sides and a bail for engaging the catches, said bail being provided with an offset portion to form a handle, an adjustable back for the seat, a foldable foot rest, and means for varying the position of the rest with respect to the seat.

4. A vehicle including in combination a supporting frame, a seat supported thereby, laterally foldable sides for the seat, means for locking the sides in position for use, said means including catches on the sides and a bail for engaging the catches, said bail being pivoted on an axis extending transversely to the length of the supporting frame, and an adjustable back for the seat.

5. A vehicle including in combination a supporting frame, a seat yieldingly supported by the frame, sides for the seat foldable inwardly upon the seat, means for locking the sides in position for use including a pivoted bail extending transversely across the frame and adapted to removably engage the

sides, a back for the seat also foldable upon the seat, and a foldable foot rest adjustably supported with respect to the seat.

6. A vehicle including in combination a supporting frame, a seat supported by the frame, laterally foldable sides for the seat, means for securing the sides in position for use including a pair of bails one of which is pivotally supported adjacent each end of the seat on an axis transverse to the length of the frame, and catches supported by the inner faces of the sides adapted to be engaged by the bails, said bails being provided with offset portions to form handles, 10 an adjustable back for the seat, and an adjustable foot rest.

7. A vehicle including in combination a supporting frame, a seat supported thereby, laterally foldable sides for the seat, means 20 for securing the sides in position for use, an adjustable back for the seat, a collapsible box-like foot rest supported for adjustment with respect to the seat, the side walls of said foot rest comprising sections foldable 25 with respect to each other, and means for securing the foot rest in any of its adjusted positions.

8. A vehicle including in combination a supporting frame, a seat supported thereby, laterally foldable sides for the seat, a foldable handle connected to the frame, means 30 independent of the handle for securing the sides in position for use, an adjustable back for the seat, a box-like foot rest supported 35 for adjustment with respect to the seat and having laterally foldable side sections, and means for securing the foot rest in any of its adjusted positions, said means including a locking member pivotally supported by 40 the rest and adapted to engage a coöperating member fixed with respect to the supporting frame.

9. A vehicle including in combination a supporting frame, a seat supported thereby, laterally foldable sides for the seat, means 45 for securing the sides in position for use, an adjustable back for the seat, a box-like foot rest adjustably supported with respect to the seat and having laterally foldable side 50 sections, means for securing the rest in any of its adjusted positions, said means including a notched member pivotally supported by the rest and adapted to engage a fixed portion of the frame, and a guard for limiting 55 the movement of the rack in one direction about its pivot.

10. A vehicle including in combination a supporting frame, a seat supported thereby, laterally foldable sides for the seat, means 60 for securing the sides in position for use, an adjustable back for the seat, a foldable box-like foot rest adjustably supported with respect to the seat, means for securing the rest in any of its adjusted positions, said 65 means including a notched member piv-

otally supported by the rest and adapted to engage a fixed portion of the frame, means for limiting displacement of the notched member, and means including a cranked shaft for disengaging the said notched member from its coöperating member to permit the rest to be adjusted. 70

11. A vehicle including in combination a supporting frame, said frame including spaced side members, a seat supported by the frame, an adjustable back for the seat, said supporting frame also including a strut extending between the side members adjacent the forward end of the frame and remote from the forward extremities of the members, a foot rest pivotally supported with respect to the seat and adjusted into different operating positions and extending between the side members of the supporting frame in advance of the said strut, and a member pivotally supported by the rest and having spaced projections adapted to engage the strut to hold the rest in any of its adjusted positions. 80

12. A vehicle including in combination a supporting frame, said frame including spaced side members, a seat supported by the frame, an adjustable back for the seat, said supporting frame also including a substantially C-shaped strut extending between the side members adjacent and opening outwardly toward the forward end of the frame, a foot rest pivotally supported by the seat and extending between the side members beyond the strut, a latch pivotally supported 90 by the rest and adapted to engage the strut between the side members for holding the rest in any of its adjusted positions, and means for detaching the rack from engagement with the strut. 95

13. A vehicle including in combination a supporting frame, a seat supported thereby, laterally foldable sides for the seat, means for securing the sides in position for use, a foldable foot rest, an adjustable back for 100 the seat, means for locking the back in position for use, said means including a toothed member adapted to engage a coöperating portion fixed with relation to the seat, yielding means tending normally to hold the 105 said member in engagement with the said coöperating portion, means for adjusting the said member against the tension of the said yielding means, the last said means including a handle supported by the back, and 110 a flexible connection between the handle and the said toothed member. 115

14. A folding vehicle including in combination a seat supporting structure, said structure including spaced members and a transverse member connecting said spaced members, an elastic member extending longitudinally to the supporting structure, with its body portion out of contact with the said structure, one end of said elastic member be- 120 125 130

ing connected to the said transverse member, a yielding support for the other end of the elastic member in advance of the said transverse member, the extremity of the elastic member beyond the said support being bent back and spaced from its body portion, and a seat supported by the said extremity.

15. A folding vehicle including in combination a seat supporting structure, said structure including spaced members and a transverse member connecting said spaced members, an elastic member extending longitudinally to and for substantially the entire length of the supporting structure with its body portion out of contact with said structure, one end of said elastic member being connected to the said transverse member, a yielding support for the other end of the elastic member in advance of the said transverse member, the extremity of the elastic member beyond the said support being bent back and spaced from its body portion, said extremity terminating short of the said transverse member, and a seat supported by the said extremity.

16. A folding vehicle including in combination a seat supporting structure, said structure including spaced members and a transverse member connecting said spaced members, an elastic member extending longitudinally to the supporting structure, one end of said elastic member being connected to the said transverse member, a support for the other end of the elastic member beyond the transverse member, the extremity of the elastic member beyond the said support being bent back and spaced from its body portion, a seat supported by the said extremity, and an additional elastic support for the seat separate from the first said elastic member and disposed between the seat and frame and supported entirely above the frame.

17. A folding vehicle including in combination a seat supporting structure, said structure including spaced members and a transverse member connecting said spaced members, an elastic member extending longitudinally to the supporting structure, one end of said elastic member being connected to the said transverse member, a support for the other end of the elastic member beyond the transverse member, the extremity of the elastic member beyond the said support being bent back and spaced from its body portion, a seat supported by the said extremity, and an additional elastic support for the seat, said additional elastic support being disposed between the said transverse member and the bend in the first said elastic support.

18. A folding vehicle including in combination a seat supporting structure, said structure including spaced members and a transverse member connecting said spaced

members, an elastic member extending longitudinally to the supporting structure, one end of said elastic member being connected to the said transverse member, a support for the other end of the elastic member beyond the transverse member, the extremity of the elastic member beyond the said support being bent back and spaced from its body portion, a seat supported by the said extremity, the said extremity of the elastic member terminating in advance of the transverse member, and an additional elastic member disposed between the seat and the supporting structure and at a point between the said transverse member and the bend in the first said elastic member.

19. A folding vehicle including in combination a seat supporting structure, said structure including spaced members and a transverse member connecting the side members, an elastic member extending longitudinally to the supporting structure, one end of the elastic member being connected to the transverse member, means for securing the other end of the elastic member to the supporting structure, the extremity of the elastic member beyond the said securing means being bent back and spaced from the body portion and terminating short of the said transverse member, a seat supported by said end, and an additional elastic member for supporting the seat arranged between the said extremity of the first said elastic member and the said transverse member and between the seat and the supporting structure.

20. A folding vehicle including in combination a supporting structure, an elastic member extending longitudinally to the structure, one end of said members being secured to the said structure, means for securing the other end of the member to the structure, the end of the elastic member beyond the said securing means being bent back and spaced from the body of the spring, a seat supported by said extremity, a foldable handle supported by the said structure, and means for locking the handle in position for use, said means including a member having sliding movement on the supporting structure beneath the said elastic member whereby the said elastic member will exert a friction on the sliding member.

21. A folding vehicle including in combination a supporting structure, an elastic member extending longitudinally to the structure, one end of said members being secured to the said structure, means for securing the other end of the member to the structure, the end of the elastic member beyond the said securing means being bent back and spaced from the body of the spring, a seat supported by said extremity, a fold-

able handle supported by the said structure, means for locking the handle in position for use, said means including a member having sliding movement on the supporting structure beneath the said elastic member whereby the said elastic member will exert a friction on the sliding member, a connection between the handle and the said sliding member, and a latch adapted to coöperate with 10 the last said member for locking the handle in position for use.

22. A folding vehicle including in combination a supporting structure, a seat supported thereby, laterally foldable sides for 15 the seat, an adjustable back for the seat, a box-like foot rest pivotally supported by one end with relation to the seat and adjustable with respect to the supporting structure, said foot rest having laterally 20 foldable side sections, the other end of the rest being free, said rest being adjustable with respect to the seat, and means for se-

curing the rest in any of its adjusted positions.

23. A folding vehicle including in combination a supporting structure, a seat supported thereby, laterally foldable sides for the seat, an adjustable back for the seat, a box-like foot rest pivotally supported by one end with relation to the seat, said foot rest 30 having laterally foldable side sections, the other end of the rest being free, said rest being adjustable with respect to the seat, and means for securing the rest in any of its adjusted positions. 35

In testimony whereof we have signed our names to this specification, in the presence of two subscribing witnesses, on this eighth day of June A. D. 1908.

ALBERT E. MCGILL.
FRANK J. BEIER.

Witnesses:

MERLE DOTY,
PERRY L. TURNER.
